PROPELLER PITCH CONTROL

Thomas B. Martin, Dayton, Ohio, assignor to
 General Motors Corporation, Detroit, Mich., a
 corporation of Delaware

Application February 1, 1944, Serial No. 520,627

9 Claims. (Cl. 170—160.21)

1

This invention relates to controllable pitch propellers, and has for an object to provide them with means for feathering and unfeathering their blade pitch condition.

One additional object is to provide propeller mechanisms with means for feathering and unfeathering, both operations being selectively controlled at the will of the pilot, and not dependent upon rotation of the propeller, yet being itself contained and self-regenerative within the rotating unit.

Another object is to provide a hydraulic pitch control mechanism with a fluid circuit having sufficient reserve of potential in the form of an accumulator to effect both feathering and unfeathering of the blades without regeneration.

A further object of the invention is to provide selective control mechanism for feathering and unfeathering of the blades that normally will be passive during constant speed operation of the propeller but instantly available at will by means of a tripping mechanism for effecting the desired control of pitch change.

A further object of the invention is to provide a hydraulic system of control for feathering and unfeathering the pitch of propeller blades, which system includes a feathering valve unit and tripping mechanism that is selectively operable to provide a mechanical impulse for the purpose of initiating flow of fluid under pressure for both feathering and unfeathering operation.

A further object of the invention is to correlate constant speed control mechanism for a propeller pitch change mechanism and a feathering control, so that preselected movement of a control member will coincidentally set the control mechanism for the shift called for and connect therewith the source of potential operative to effect the selective extreme shift.

Another object of the invention is to provide a hydraulic system of control for a constant speed propeller and selective control means for feathering and unfeathering the propeller to be effected by a trippable feathering valve control unit, inserted in the fluid circuit between the pressure developing means and a distributor valve unit with a relief branch safeguarding the system against damage from unwanted pressures.

Another object of the invention is to provide a hydraulically controlled constant speed propeller with means for feathering and unfeathering the blades, that enable construction and assembly complete as a unit suitable for mounting on an available engine or propeller shaft without subsequent assembling in the field.

2

A further object of the invention is to provide a feathering propeller with feathering control units that are mountable and removable from the propeller structure without dismounting the propeller from its driving shaft.

10 A further object of the invention is to provide a feathering propeller with an accumulator and feathering control valve unit that may be removed for repair or service without removing the propeller from the aircraft.

15 Yet another object of the invention is to provide a large capacity accumulator for a feather propeller that will not interfere with spinner support or with cannon fire through the axis of the propeller shaft.

20 Still another object of the invention is to provide a feathering propeller with an annular accumulator mounted concentric of the propeller shaft and for rotation with the propeller, and relatively immovable fluid connections with the fluid pressure system controlling the pitch of the blades.

25 Another object of the invention is to provide a self-contained hydraulic actuated constant speed controllable pitch propeller with feathering and unfeathering mechanism devoid of all external fluid connections, but having mechanical connection with a cockpit control whereby the speed level of constant speed control can be selected, and the feathering and unfeathering effected at will of the pilot.

30 Yet another object of the invention is to provide a feathering control for hydraulically actuated pitch shifting propellers that is embodied in a unit removable from the exterior of the regulator and provided with a fluid filter inserted in the pressure circuit of the system.

35 Another object is to provide an aircraft propeller capable of constant speed control by blade shift within a working range, and also capable of superposed control for blade shift to a range outside of the working range, with means operable at will to return the blade pitch to the working range.

40 45 Further objects and advantages of the present invention will be apparent from the following description, reference being had to the accompanying drawings wherein a preferred embodiment of the present invention is clearly shown.

50 In the drawings:

Fig. 1 is a longitudinal sectional view of a feathering propeller mechanism involving the present invention, it being a view substantially as indicated by the line and arrows 1—1 of Fig. 2.

55 Fig. 2 is a transverse sectional view through the

regulator of the control mechanism substantially as indicated by the line and arrows 2—2 of Fig. 1.

Fig. 3 is a plan view of the trip mechanism and relief valve assembly substantially as indicated by the arrow 3 of Fig. 5.

Fig. 4 is a sectional view therethrough substantially as indicated by the line and arrows 4—4 of Fig. 3.

Fig. 5 is an enlarged fragmentary sectional view showing that portion of the fluid circuit from the accumulator to the control valve with its tripping mechanism.

Fig. 6 is a similar view of a modified form of the invention.

Fig. 7 is a schematic view illustrating the fluid circuit for the complete control of the propeller mechanism.

Fig. 8 is an enlarged transverse sectional view through the feathering control valve substantially as indicated by the line and arrows 8—8 of Fig. 7.

Fig. 9 is an enlarged sectional view of the accumulator charging and feathering control valve unit detached from any supporting or connected structure.

Referring specifically to the drawings, 10 indicates an engine nosing or gear casing from which rotatably extends a propeller shaft 12 seating a rear cone 14, and by means of splines 16 driving a hub 18 where it is held by a front cone 20 and a shaft nut 22. The hub 18 provides radially extending sockets 24 within which are secured propeller blades 26 rotatable about pilot bearings 28 and within thrust bearings 30. There are a plurality of sockets and blades, and each blade 26 is hollowed out at its root to enclose a torque unit 32 consisting of a cylinder 34 drivingly connected to the blade and housing a piston 36 movable the length thereof and connected by spiral splines 38 with the cylinder and by other splines 40 with a hollow spindle 42 fixed to the blade bearing boss 44 supporting the pilot bearing 28. The piston is double acting, in that it divides the cylinder 34 into two collapsible or expansion chambers, one 46 at the outward end of the cylinder and the other 48 at the inward end of the cylinder. Fluid pressure applied to either end of the piston causes it to move along the cylinder and in so doing rotates the blade within its bearings. Equal and coincident rotation of all of the blades is assured by fitting each blade with a gear segment 49 that meshes with a master gear 51 mounted on antifriction bearings 53, the outer race 55 of which is secured in an enlarged bore 57 of the hub 18 in front of the bearing bosses 44. A thrust plate 59 secured to the forward end of the hub for keeping the bearing in place, has a sleeved extension 61 whose end is disposed beneath the bosses 44 and is radially spaced about the nut 22. Thus, rotary motion transmitted to each of the blade gears 49 is also applied to the master gear 51, which insures that no one blade will be shifted faster, or further than any of the other blades of the propeller. The application of fluid under pressure is controlled by a regulator 50 through tubular passages 52 and 54 one of which connects to a pipe 54a secured in the bearing boss and slidably extending through the piston 36.

The regulator 50 is shown chiefly in elevation in Fig. 2, and as indicated in Fig. 1, comprises an annular plate 56 joined with a cover shell 58 and an adapter assembly 60 to provide an annular chamber forming a reservoir 62 housing the propeller control apparatus and a quantity of 76

fluid operating medium. The regulator so fashioned is secured on a rearwardly extending sleeve portion 64 of the hub 18 so as to be concentric with the shaft 12 and is there held by means of a sleeve nut 65 extending within the adapter 60 and threading onto the extension 64. The plate 56 embodies control passages 66 and 68 connecting with the tubular passages 52 and 54 respectively and also a pressure supply passage 70 extending from a pump or pressure creating device 72 to a juncture block 73 for relief and certain control valve units, and also a feeder passage 74 leading to a distributor valve station 76. Control passage 66 has a plurality of ports 78 each of which communicates with a tubular passage 52 leading to a chamber 46 of the torque unit so that all of the chambers 46 are exposed to the control passage 66, and the control passage 68 has a plurality of ports 80 similarly connected to the tubular passages 54 and chambers 48.

At the station 76 there is located a governor valve unit 82 that embraces a porting sleeve 84 suitably mounted at the station and having a middle port 86 always open to the fluid in the passage 74, and axially spaced ports 88 and 90 opening to the control passages 66 and 68 respectively. The porting sleeve 84 is so mounted that its bore 92 is disposed radially of the axis of propeller rotation, and so that a valve plunger 94 fitted therein is capable of movement along the bore of the sleeve in response to domination of centrifugal force or spring force opposing it. The valve plunger 94 has a pair of spaced lands 96 and 98 which are positioned so as to cover the ports 88 and 90 respectively when the centrifugal force and spring force are in equilibrium, or are balanced. The valve plunger 94 is articulated at 100 with a lever 102 that extends substantially normally thereto from to rest upon a movable fulcrum 104 where it is maintained under the urge of a spring 106. The governor valve so constituted is adapted to effect constant speed operation of the propeller, whose speed level is determined by the position of the fulcrum 104 along the length of the lever 102 which determines the relation of the spring force and centrifugal force acting upon the valve plunger and its linkage.

Determination of the speed level of the control is made by movement of the fulcrum 104, which is supported by a carriage 108, toward and from the line of force exerted by the spring 106. Rigidly mounted on the plate or the governor valve unit there are guides 110 that extend along the length of the lever 102 and support the carriage 108 in sliding relation. An extension 112 of the carriage 108 extends into an annular groove 114 of a control ring 116 which is disposed about and movable along the length of the adapter assembly 60. Rotation of the control ring is prevented by guide rods 118 passing therethrough and anchored in the adapter assembly which comprises a sleeve 120 extending across the reservoir 62 to engage bearings 122 and 124 in the members 56 and 58 along with sealing means that prevent leakage of fluid from the reservoir. Secured to the sleeve 120 and extending outside of the reservoir there is a guide ring 126 mounted on a pilot plate 128 and forming an annular channel within which there is oscillatably disposed a ring gear 130 with a lever 132 attached, which ring gear is in mesh with a plurality of pinions 134 carried by screw shafts 136 journaled in the sleeve 120 so as to thread into and out of the control ring 116. The

adapter assembly ending with the pilot plate 128 has a journal bearing in the regulator by reason of the bearings 122 and 124, but is restrained from turning with the propeller mechanism by a lug or stop means 138 secured to the engine nose 10 and entering a slot or notch 140 of the pilot plate 128. Thus while the propeller is in operation the regulator 50 is rotated about the adapter assembly 60, and advantage is taken of that to provide a toothed flange 142 on the sleeve 120 inside of the reservoir for engaging a spur gear 144 of the pump 72, so that rotation of the propeller will also effect rotation or driving of the pump 72.

As schematically shown in Fig. 7 of the drawings, driving of the pump 72 withdraws fluid from the reservoir 62 through the intake 146 and delivers it under pressure to the passages 70 and 74, as will presently appear, by which it is delivered to the port 86 of the governor valve unit. Assuming the propeller to be operating at some constant speed determined by the setting of the carriage and fulcrum 104, then the valve plunger 94 will be in the equilibrium position and the lands 96 and 98 will cover both of the ports 88 and 90, so that there will be no inequality of pressure applied to either side of the piston 36 in the torque units. Hence, no shifting of the blade pitch. Assuming for the purpose of illustration that there occurs a condition of overspeed, in which centrifugal force becomes dominant and causes the valve plunger to move radially outward of the equilibrium position, that movement causes the port 90 to be connected with the pressure port 66 and pressure is thereby applied to the piston 36 for increasing the pitch of the blade. At the same time the port 88 is opened to the end of the porting sleeve by which the opposite side of the piston 36 is relieved and drained to the reservoir 62. For a condition of underspeed, the spring 106 becomes the dominant force and the valve plunger 94 moves inward to uncover the port 88 to pressure of port 86, and the port 90 is opened to drain as shown in Fig. 7, and which conditions the piston 36 to rotate the blade to a reduced pitch position. In either instance the blade angle is quickly corrected to effect constant speed operation within the working range selected by positioning of the fulcrum 104.

Under operating conditions it sometimes becomes desirable or necessary to shift the blade pitch to an extreme position outside of the normal or working range, and in some instances continued rotation of the propeller cannot be relied upon to provide the necessary energy to accomplish that desired shift. That is especially true when the propeller has been brought to rest for one reason or another. In order to have available for use at those times a source of pressure that can be relied upon and used to move the blades to an extreme position, an accumulator 147 is mounted on the propeller with fluid connections 148 to the hydraulic system and a control valve 150 is provided by which the charge and discharge of the accumulator can be controlled.

The accumulator control valve mounts on the outside of the regulator plate 56 by threading into the juncture block 73 as shown in Figs. 1, 5 and 9, and comprises a chambered member 152 necked down to receive the accumulator tube 148 where it is fitted with a valve seat 154. Cooperating with the seat 154 there is a conic valve head 156 having a tubular extension 158 which extends through an opening in a diaphragm 160 where it is held by a retaining nut 162 axially spaced from the diaphragm at 163, and forming a guide for

the passage of a trip rod 164 operable from within the regulator. The diaphragm 160 is carried by a piston member 166 that slides within the chambered member 152 and is under the urge of a spring 168 normally to close the port of the seat 154 by the valve head 156, and the diaphragm has a plurality of apertures 170 around the valve head so as to subject both sides of the diaphragm to the same pressure. Obviously, the number of such apertures is not material and only one can be used if desired. The piston 166 has a tubular extension 172 centrally apertured at 174 to slide over a tubular boss 176 of a thrust head 178 secured in the open end of the chambered member 152 by a snap ring 180. In the side walls of the tubular boss 176 there are valve ports 182 controlled by the apertured portion 174 of the piston extension, and other ports 184 that open from the bore of boss to the outside end of the piston, while the end of the boss is apertured at 185 to permit passage of the trip rod 164. Seated against the thrust head 178 there is a spool member 186 whose side wall is apertured at 188 for passage of fluid, and which is so disposed as to seat one end of the spring 168 by which the spool is held against the thrust head 178, the periphery of the spool member being surrounded by a screen or foraminous member 190. The junction block 73 is apertured at 192, Figs. 5 and 7, for communication with the line 70 from the pressure source, and the skirt of the chambered member 152 has slots at 194 to permit passage of fluid to the outside of the spool from where fluid flows through the ports 182 and 184 to the bore of the boss and around the trip rod 164 along an axial bore or passage 196 of the juncture block 73 to which is joined the passage 14. The thrust head 178 is socketed at 179 and there seats a seal ring 181 adapted to engage over the end of a tubular boss 183 as an extension of the junction block 73 insuring that there is no direct cross flow between the passages 70 and 74 as shown in Fig. 7, and thereby connects 196 directly with the bore of boss 176. The fluid under pump pressure also flows along the rod 164 through the aperture 185 at the end of the tubular boss 176, through the retaining nut 162 to unseat a ball check valve 197 located in a fluted bore 198 of the valve head, and thence through an aperture 199 into the accumulator passage 148. The ball check valve 197 is adapted to be responsive to the pressure differential between the accumulator pressure and the pressure in the system so as to cause the valve to move longitudinally within the passage 198. Pressure in excess of that permitted to pass to the accumulator 147 builds up in the passage 196, Figs. 4 and 7, and exerts itself along a groove 200 between the regulator plate 56 and a mounting block 202 for the trip mechanism to an enlarged bore 204 of an aperture receiving one of the screw-devices 206 for mounting the block on the plate, and thence through a passage 207 to the interior of a pressure control valve 208. The valve 208 has a plunger 209 with a land 211 that normally prevents escape of fluid through apertures 210, by means of centrifugal force plus the pressure of a spring 212, but presenting an area exposed to the pressure of the line by which the exhaust ports may be opened.

The trip rod 164 is slidable through the block 202 and has its inner end 214 flattened as it passes through the guide 162 to engage the ball, and is also sufficiently smaller than the bore of the tubular boss 176 which receives the rod to permit

the passage of fluid when the accumulator is being charged. The block 202 is slotted at 215 and into this slot the outer end of the rod 164 extends. A lever 216 which is supported on a pivot 218, as best shown in Figs. 6 and 7, has an arm 220 which extends into the slot 215 and engages rod 164, the arm normally resting against a stop pin 222. The lever 216 has a cam portion 224 at its free end that is engageable by a cross pin 226 mounted in and adapted to traverse the length of slots 228 which are provided by a carriage 230 having rollers 231 which are movable along guide ways 232 secured to the block 202 by screws 203. The carriage 230 has a depending extension or shoe 234 which engages the groove 114 of the control ring 116 which is moved to control the governor valve as heretofore described.

The accumulator 147 is of rigid wall construction and is mounted on the forward end of the propeller hub so as to be coaxially disposed therewith and not disturb the balance of the entire assembly. Within the contemplation of the invention, the accumulator may take the form of an annular chamber such as shown in Figs. 1, 5, and 7, or it may take the form of an axially disposed cylinder of the form shown in Fig. 6, in either instance the accumulator being capable of assembly with the propeller hub before the propeller is mounted on the shaft, and assisting in the setting or withdrawing of the hub-shaft nut by which the propeller is secured on the shaft. In the annular type, per Fig. 1, the accumulator preserves the hollow characteristics of the shaft suitable for cannon fire and for passage of a second shaft for a second propeller, as in a counter-rotating structure. In either instance the accumulator or its mounting serves a secondary function in piloting a spinner for fairing the propeller structure.

Referring to the annular type of accumulator shown in Fig. 1, there are a pair of radially spaced cylindrical walls 240 and 242 each having a flange 244 and 246 respectively fitted with seal rings 248 engageable with the cylindrical wall of the other so as to form a fluid tight annular chamber adapted to enclose a rigid piston shell 252 at the inner edge of which adjacent wall 242 is a channel in which is a sealing ring 254, and on the outer surface of which is a channel which receives a sealing ring 256 slidably engaging the surfaces of the walls 242 and 240 respectively. The piston shell has a skirt 258 extending therefrom which is apertured at 260 into an annular groove 262 to reduce the metal to metal contact between the skirt and cylinder 240. Thereby, the concentric shells form a normally closed chamber that is divided by the piston into what may be termed a loading chamber 250, and a pressure chamber 251, the flange 246 being fitted with a Schrader type air valve 264 by which the loading chamber may be pumped full of air to the desired pressure, while the cylinder 240 has a nipple 266 formed thereon to which the tube 148 may be secured by a clamp nut 268. The cylinders and piston member may be assembled as a unit in which position they are held by a spring ring 270 in the open end of the cylinder 240 acting as a stop for the flange 246 of the inner cylinder 242. For mounting the accumulator the flange 244 is projected outwardly to form ears 272 through which extend some of the screws 274 by which the thrust plate 59 is secured to the end face of the hub 18. The flange 244 has an extension 276 which projects into the end of the sleeve extension 61 of the thrust plate

so that the accumulator is properly concentric with the axis of propeller rotation.

Received within the inner cylinder wall 242 of the accumulator there is a rotatable sleeve 278 that has castellations 280 which cooperate with the castellations of the nut 22 by which the latter may be turned from a point anterior to the accumulator, where the sleeve has slots 282 to receive a wrench. Against a shoulder 284 of the sleeve there bears a spring 285 that also engages a seating ring 286 abutting the flange 244 and the end of cylinder 242, which spring operates to keep the sleeve and nut in engaged relation. It is desirable to prevent relative rotation between the cylindrical members 240 and 242 so a cross pin 288 located in the flange 244 extends into a notch 290 of the cylinder 242 where it is kept from appreciable endwise displacement by the parts 61 and 278 as shown in Fig. 5. In that figure is also shown means for supporting the forward end of the spinner and for locking the shaft nut against loosening. The spinner comprises a conic shell 292 whose base end is supported in any desired manner and terminates at its apex with a reinforcing ring 294 secured thereto by screws 296 under one of which there is a locking clip or plate 298 adapted to engage one of the slots 282.

In the form of mounting shown in Fig. 6, the accumulator is formed from a cylindrical wall 300 whose outer end is closed by a head 302 seating against a flange 304 of the cylinder, and sealed by a ring 306, the head member supporting the air valve 264 and threadedly receiving a rod or other member 308 for support of the spinner. The opposite end of the cylinder is notched at 310 to receive the castellations of the nut 22 and is of a diameter to slidably fit within the nut receiving bore of the hub beneath the bosses 44 where sealing rings 312 prevent fluid leakage, a snap ring 314 within the cylinder operating to retain an impervious head member 316 the periphery of which is sealed by ring 318. Within the cylinder 300 there is a piston 320 having a skirt 322 at each end of which there is a sealing ring 324 engageable with the inner surface of the cylinder. As in the earlier described device, the skirt 322 extends toward the loading chamber 250 and is engageable with the head or flange 302 so as to define the minimum volumetric content of the loading chamber. In both cases the pressure chamber 251 is practically collapsible as shown in full lines in Figs. 5 and 6 of the drawings, but upon increase of pressure is expandable to the extent of that delineated by the dot and dash line showing in the same figures. Here, the cylinder 300 provides an opening 326 from the pressure chamber 251 that opens into a passage 328 of the hub 18 and which leads to the control valve 150 as herein explained, in this instance the passage 328 taking the place of the tube 148. Intermediate the length of the cylinder 300 there is an angled flange 330 receivable by the bore 332 of a thrust ring 334 secured to the face of the hub and forming the outer race 336 of the bearing 53, there being a seal ring 338 for prevention of leakage, and snap ring 340 that maintains the assembly in proper relation. The terminal end of the thrust ring 334 is notched at 342 for selective reception of a tang 344 on a locking ring 346 having on its inner periphery teeth 348 adapted to engage the notches of a toothed flange 350 on the cylinder 300. When the ring is in place a snap ring 352 secures the lock ring against dislodgement. Thus,

the nut 22 is prevented from loosening, since it is engaged by the end of the cylinder 300 at 319 and the cylinder is prevented from turning by the lock ring 346 engaging the notches 342 and the teeth of the flange 350. With the locking ring 346 disengaged, the cylinder can be rotated to tighten or loosen the shaft nut 22, by applying a wrench to the toothed flange 350.

In either form of construction the accumulator is formed by rigid wall members and their joints are sealed against fluid leakage. That is done preferably by using soft or pliable rubber bands or rings lodged in grooves of such dimension that assembly of the parts will effect some compression of the rubber to accomplish the seal. When the parts are assembled they will be maintained in distended relation by the loading pressure in the chamber 250, in such instance the pistons being moved to the extreme right hand of the views such as to practically collapse the pressure chamber 251.

To state generally, and referring to Fig. 5, the accumulator provided for storing oil under pressure for feathering and unfeathering is shown bolted to the front of the hub in place of the spinner adapter. It is an annular piston type of accumulator with the center hole large enough to provide the same size bore for the cannon as heretofore used. The outer shell is bolted to the hub and the inner shell is sealed to the outer shell at both ends. A snap ring holds the assembly together and is safe against centrifugal force. All seals including the piston seals may be round rubber rings. Since these rings do not require close tolerances, they are difficult to misassemble, and have proved to be reliable as a seal for nitrogen at 1000 p. s. i. and reliable against pumping of oil when used as piston rings between oil and nitrogen. However, other types of seals may be used, such as chevron, or rings of square section with reinforcing edges.

Near the hub end of the accumulator the oil delivery tube 148 is mounted by means of a flexible tube-connector as shown. This consists of a C-section rubber ring slipped over the flared end of the tube and held down with a screw cap. This cap is knurled and has no wrench flats. It is to be tightened by hand only and safetied to a nearby bolt. This connection is leakproof and will maintain its flexibility at high pressures. A high pressure Schrader valve 264 is fitted to the forward end of the accumulator for preloading and is arranged to protrude from the bolt circle at the nose of the spinner for convenience and accessibility. Included in the accumulator assembly is a central sleeve received by the accumulator and arranged to have driving connection with the shaft nut at its inner end and to extend forward of the accumulator at its outer end to receive the spinner nose. Its outer end is arranged with 9 wrench slots so that the propeller may be installed on the airplane complete with spinner, thereby eliminating a major percentage of the time required for installation. The nut is locked by a locking plate which engages the slots in the sleeve end and mounts under the four fillister head screws on the exterior of the spinner nose as shown. Eight equally spaced holes are provided in the locking plate so that the same indexing arrangement for locking is provided as before. A coil spring surrounding the sleeve maintains it against the shaft nut to prevent chatter. In no case, however, could the sleeve slip forward far enough to disengage the nut.

In operation the accumulator piston is mechanically stopped so that it takes a predetermined maximum volume of oil from the regulator and no more. This definitely determines the maximum and minimum oil level in the regulator. The effect of changing temperatures on the preload pressure may then be taken as a change in maximum pressure or be distributed between pressure and volume as desired by choosing the preload pressure accordingly.

The piston has another advantage in that it definitely divides the air and oil so that there is no question as to their distribution in the centrifugal field. Let it be assumed that the piston will draw 75 cu. in. of oil from the regulator, and 48 cu. in. are required to shift the blades from the low pitch stop to feather. This leaves enough remaining capacity for unfeathering back to 57° blade angle. This assumes the worst conditions for feathering and no assistance from the pump. The pump will assist somewhat during feathering, and as soon as wind-milling is established on unfeathering the pump will continue to decrease the blade pitch slowly. A large volume for preloading is provided in the accumulator, and the air preload pressure is about 400 pounds per square inch with the accumulator empty.

As soon as the propeller is rotated the regulator supporting the pump is rotated about the adapter assembly by which the toothed flange 142 effects rotation of the pump gear 144 developing a fluid pressure within the pump 72, Figs. 2 and 7. That pressure is communicated through the passage 70 to the feathering control and accumulator charging valve 150, and on to the governor valve unit to be used for pitch shifting functions as has been explained. The entire fluid circuit in its simplest form is illustrated in Fig. 7, where it will be observed when compared with Fig. 9 that the fluid under pressure flows from the pressure passage 70 through the opening 192 of the junction block 73 to the space around the screen 190 of the spool to be there filtered, and after passing through the screen the fluid flows through the openings 188 and around the spring 168 and through the ports 184 to the interior of the hollow boss. The valve 154, 156 will then be closed and the ports 182 will be restricted, so that the fluid under pressure flows through the opening 185 in the end of the tubular boss 176 around the rod 164 to the inside of the piston extension 172 and thence through the bore of the guide nut 162 and around the flattened portion 214 of the rod 164 to unseat the ball check valve 197, and thence through the passage 199 to the pressure chamber 251 by way of the tube 148 or the passage 328. As the accumulator is charged with fluid under pressure from the pump 72, the piston member 252 or 320 is moved away so as to increase the compression of the gas or air in the loading chamber 250. That continues until the piston engages the stop between the end of its skirt and the head of the cylinder. Pressure developed in excess of that defined by the loading chamber is also exerted on the other fluid passages connected with the passage 196 of the junction block 73. Thus, the pressure of the line will be effective through the passages leading to the governor valve unit 82 and to the interior of the pressure control valve 208. In the actual construction as shown in Figs. 1 and 2, the pressure control valve is disposed with its plunger 209 arranged along a radius of rotation of the regulator so that centrifugal force acting on the plunger assists the spring 212 in withdrawing the land 211 from

the ports 210, substantially as shown in Fig. 7. The line pressure in the passage 207 is applied to the full area of the land 211, and when it develops to the point of overcoming centrifugal force and force of the spring 212 applied to the plunger, it moves the plunger to a position to open the ports 210, which immediately relieves the pressure in the line and spills some of the fluid medium back into the reservoir 62. Thus, the pressure control valve 208 variably controls the maximum of pressure that may be carried in the system since the valve 208 responds to two variable forces opposing each other, one being centrifugal force and spring force applied to the plunger 209 moving it outward, and the other being pressure in the system applied to the area of 211 moving the plunger 209 inward. With the propeller mechanism rotating at high on-speed, the centrifugal force exerted on the plunger 209 and assisted by the spring 212 will permit a maximum pressure to exist in the fluid pressure system, the pressure of the system always present at the end area of land 211 in opposition to the centrifugal and spring forces, tends to open the ports 210, upon approach to the maximum pressure. With the propeller operating at a low on-speed, the centrifugal force acting upon the valve member 209 would be less, wherefore the combined effects of spring force and centrifugal force opposing the pressure upon the end area of land 211 would be lower and permit the opening of ports 210 at a lower system pressure than for a fast rotating propeller. The maximum pressure limit may be selected by calibration of the spring 212, the mass of plunger 209, the area of land 211, and the radial location of the valve unit on the plate 56, and the maximum pressure limit chosen will depend upon the needs of the propeller mechanism to be served. A small two bladed propeller will not need as high an operating pressure, nor will it require as large a flow of fluid as a large four bladed propeller, the determining factor being that the system will always carry sufficient fluid pressure to actuate the torque units whenever the governor valve 82 moves to open one of the control ports.

During this cycle of operation the feathering control valve will be in the condition illustrated in Figs. 5 and 9, with the piston 252 in the illustrated dot and dash line position. To make available the pressure of the accumulator for feathering the blades 26, the lever 132 (Fig. 1) is oscillated so as to move the control ring 116 forward along the sleeve 128 to effect the position shown in Fig. 5, which moves the carriage 230 to a position against the regulator plate 56. That movement of the carriage first upsets the equilibrium of the governor valve 82 so that the valve plunger 94 is now in an outward position (downward instead of upward, as shown in Fig. 7), connecting the pressure supply port 86 to the increase pitch port 90 without any restriction due to partial covering of the port 90 by the land 98. The piston chamber 48 then being connected directly with the passage 74 immediately reduces the pressure of the system to a low value, since the governor is now nonoperative to correct for loss of speed. Also the pressure in the system supplied by the decreasing rotation of the pump effects increased pitch shift of the blades which rapidly reduce the speed of rotation and a decided loss of pressure potential in the system up to the back side of the piston extension 172 and around the spring 168. The second event incident to movement of the carriage carries the cross pin 226 beneath the

cam 224 of the lever 216 whose arm 220 depresses the trip rod 164 which upon being moved inward of the valve unit upsets the ball check valve 197, allowing a spurt of pressure fluid from the accumulator through the port 199 and the guide nut 162 to the inside of the piston extension 172. From there the pressure of the accumulator is exerted on the full area of the piston 166 against the low pressure around the extension 172 which causes the piston to move in compressing the spring 168. That movement of the piston uncovers the ports 182 and also withdraws the conic valve 156 from its seat 154 substantially as shown in Fig. 7. The direct effect of the accumulator pressure is immediately and greatly increased from the area of the port 154 to the full area of the piston 166, which for the time being withholds the valve 156 from reseating. The fluid in the accumulator under high pressure then flows through the port 154, the apertures 170 of the diaphragm and inside of the piston extension, then through the ports 182 and passages 196 and 74 to the governing valve unit 82 where it is manifest at the port 66 as shown in Fig. 7. At the same time that the carriage 230 is moved against the regulator plate 56, the carriage 108 for the governor valve unit will also be moved to a position such that the fulcrum 104 will be between the spring 106 and the valve plunger 94, causing the plunger to be moved radially outward as indicated by the dotted line position shown in Fig. 7. That as has been stated will connect the control passage 54, 68 and port 99 with the pressure supply port 86 so that the pressure of the line will be exerted in the chamber 48 of the torque unit for movement of the blade to the feathered position, the chamber 46 of the torque unit relieving itself by fluid flow through 54a, 52, 66, 88 and 92 in returning to the reservoir 62. As soon as the feathering position is reached the pressure differential on the piston 166 is eliminated and the spring 168 effects reclosing of the valve 154, 156 substantially as shown in Fig. 5. The capacity and design of the accumulator is such that only a portion of its potential will be used in effecting the feathered movement of the blades.

To unfeather the blades, the cockpit control is manipulated to effect oscillation of the lever 132 for moving the control ring 116 to the aft end of the adapter sleeve, such as shown in full lines in Fig. 7, where it appears that both carriages 108 and 230 have been moved to the right. That movement of the carriage 108 conditions the governor valve unit 82 for connecting the pressure supply port 86 with the pitch decrease port 88. That movement of the carriage 230 effects another cammed movement of the lever 216 which again moves the trip rod 164 to repeat the described operation of the feathering control valve. However, in this instance the governor valve unit connects the pressure source with the pitch decreasing side of the torque unit instead of with the pitch increase side, and the pressure of the accumulator is then available to shift the blades into the working position, or sufficiently that windmilling of the propeller will be effected and may be sufficient to crank the motor for restarting. Thus, the propeller may be feathered and unfeathered at will while in flight, or even while the plane is standing still on the field or in the hangar. It is not necessary that the engine be running when either feathering or unfeathering is accomplished, for the accumulator, once it is

charged, retains its potential until the trip valve is manipulated.

To summarize operation of the control valve 150, and referring to the section of the regulator shown in Figs. 5 and 7 there is shown a tripping mechanism inside the regulator and an externally removable valve and filter assembly in line with it on the outside of the forward wall. The purpose of the tripping mechanism is to provide a mechanical impulse to the valve for the purpose of initiating flow from the accumulator both for feathering and unfeathering. This is done by providing a carriage slidably mounted on rollers and carrying a shoe which engages the control ring in the same manner as the governor shoe. The rails of the carriage are slotted to carry a roller between them as shown at 226 and 228. This roller can slide back and forth about $\frac{1}{8}$ inch. The carriage is shown in the feathered position in Fig. 5. Assume that it is moved back to the other end of its travel and then moved to its position as shown. Nothing will happen until the roller 226 is engaged by the cam 224 of the bell crank 220. The bell crank will then be rotated about its pivot 218 and its upper arm will push the rod 164. When the roller passes the apex of the cam it will move out from under it and along its slot, releasing the bell crank which then drops back against the pin 222. At the same time the governor 82 in another location in the regulator has been shifted by the control ring 116 into positive high pitch position which directs the blades to feather upon application of hydraulic pressure. To unfeather the blades the control ring will move the carriage in the opposite direction until the roller 226 has reached the other end of its slot 228 whereupon it will be forced past the cam 224 again, and will repeat the operation of pushing and releasing the rod 164. At this time the governor will be moved by the control ring into its decrease pitch position thereby directing the blades to unfeather upon application of hydraulic pressure. The lost motion of the roller 226 in its slot 228 also serves to prevent accidental tripping of the rod 164 if the control ring should drift slightly due to vibration or other disturbances while the propeller is in feathered condition.

In order to control the application of hydraulic pressure during all this, an arrangement of valves is provided in the outer end of the externally removable filter cap. Oil under pressure from the accumulator enters at the forward end of the cap and is normally sealed by the valve plunger 156 and the check ball 197. Pressure oil from the pump 72 enters the cavity in the regulator housing behind the threads 151 which hold the cap. This oil is directed through milled slots 194 in the inner end of the cap and through the filter screen 190. It then flows toward the center of the cap and through the holes 184 into the center tube. From there it flows into the regulator casing where it is directed to the governor 82 and to the pressure control valve 208 through appropriate passages in the body of the tripping mechanism to which the valve 208 is attached. This provides normal pump flow for constant speed operation of the governor. Fluid from the pump can also pass into the outer end of the cap at 185 and if the pump pressure exceeds the pressure in the accumulator it will move the check ball 197 and pass on into the accumulator for filling. The spring 168 holds the plunger 156 firmly on its seat 154 against accumulator pressures up to about 1200 p. s. i. Above this pressure it acts

as a relief valve against pressure increases which may result from rising temperatures if, for instance, the airplane is left standing in the sun with the accumulator full.

When it is desired to feather the propeller the control ring 116 is moved to extreme feather position and three things happen at once: the governor 82 is shifted to positive high pitch position, the pressure to the governor drops from that established by the pressure control valve 208 to that required to move the blades, and the check ball 197 receives an impulse from the rod 164 and passes a shot of oil from the accumulator into the space behind it. This shot of oil again raises the pressure in its immediate vicinity and acting on the larger area of the piston 166 causes it to move against the spring 168. The plunger 156 also moves back allowing a flood of oil to rush from the accumulator against the piston 166. Piston 166 moves away and uncovers the holes 184 allowing the accumulator flow to enter the regulator and flow to the governor. When the blades reach the feathered position the flow of oil to the torque units ceases and pressures are equalized throughout the system. There is no longer a pressure drop through the holes 184 and the spring 168 is then able to move the piston 166 back until the plunger 156 again seats itself. The pressure in the system may then leak off without further drain from the accumulator.

When it is desired to unfeather the propeller the control ring is moved in the opposite direction to a position shown in Fig. 7 and the above series of events is repeated, the only difference being that the governor 82 is thereby moved to its decrease pitch position and the blades turn in the opposite direction.

While the embodiment of the present invention as herein disclosed, constitutes a preferred form, it is to be understood that other forms might be adopted, all coming within the scope of the claims which follow.

What is claimed is as follows.

1. A controllable pitch propeller unit comprising, a hollow shaft, a propeller hub mounted on the shaft and having radially extending blade sockets, blades each having a fluid motor mounted for rotation in the sockets, a fluid operated regulator including a fluid charged reservoir, a pump operable upon rotation of the propeller and a governor valve for supplying fluid under pressure to actuate the blade motors, said regulator being mounted on the hub in the rear of the blade sockets, an annular accumulator mounted on the hub in front of the sockets, conduit means connecting the accumulator with the pump and governor valve and including a selectively operable control valve for admitting fluid stored in the accumulator to the blade motors, a tubular extension aligned with the hollow shaft and extending axially within the annular accumulator, a nut for securing said propeller hub to the hollow shaft, means on said extension engaging said nut and effective to adjust the nut upon movement of said extension, and means for locking said extension in adjusted position so as to hold the hub retaining nut in position and prevent loosening thereof.

2. A controllable pitch propeller having blades adjustable about their axes, reversible fluid motive means for actuating the blades through two adjoining ranges of blade inclination, one of which ranges is for normal constant speed operation, and the other of which is for supplemental blade pitch control, a fluid pressure sys-

tem for the fluid motive means, speed responsive means for controlling the blade angle through the working range, an accumulator in communication with the fluid pressure system, a differential pressure responsive valve interposed in said fluid pressure system for connecting the accumulator to said system, said valve including a movable means responsive to and operated by the pressure of the fluid in the fluid pressure system for controlling the charging of the accumulator, means for operating said valve to effect communication between the accumulator and said fluid motive means so as to communicate the pressure of the accumulator to said fluid motive means, means for controlling the operation of the speed responsive means and adapted to be operatively connected to said valve operating means to effect operation of the valve operating means to control the communication of fluid pressure from the accumulator to said fluid motive means in order that the blade pitch may be shifted as desired from one pitch range to the other.

3. A propeller unit having pitch shiftable blades, blade motors, and a hydraulic regulator for adjusting the blades to a selectable rotative speed for an aircraft, comprising in combination, a self-contained fluid pressure system within the propeller unit, speed responsive means for altering the blade pitch between a maximum and a minimum blade angle, manual means for operation of said speed responsive means for selecting the rotative speed of operation, a rigid walled cylinder, a rigid piston within the cylinder dividing it into a preloading chamber and a pressure chamber, a fluid connection between the pressure chamber and said system, a valve unit interposed in the fluid connection between the pressure chamber and system and movable by the fluid in the fluid pressure system to a position to admit fluid under pressure from the system to the pressure chamber of said cylinder whereby the preloading chamber is compressed and fluid under pressure is stored in said pressure chamber, a trip rod operable upon the valve for moving said valve to a position to effect communication between said pressure chamber and the fluid pressure system so as to communicate the pressure of said chamber to the fluid pressure system independent of propeller rotation in order to effect feathering or unfeathering of the propeller, and means including a part of said manual means for effecting movement of said trip rod.

4. In a controllable pitch aircraft propeller having shiftable blades and fluid pressure actuated means for shifting the blade angle between high and low pitch limits of a working range and a self-contained fluid pressure developing means with a pressure line for supplying fluid under pressure to said fluid pressure actuated means, the combination of means for selectively shifting the blades to an angle outside of the working range and for returning the blades to an angle within the working range, including a rigid walled accumulator mounted on the propeller, means connecting the accumulator and pressure line including a valve unit having a check valve permitting fluid flow from the line into the accumulator, a spring pressed piston and valve head supporting the check valve and normally closing a port against return flow from the accumulator, a trip rod for upsetting the check valve and for admitting the full force of the accumulator pressure to the piston for withdrawing the valve head whereby the fluid pressure of the accumulator is exerted on the pressure line, and means for

actuating the trip rod and for coincidentally connecting one side of the pressure actuated means with the pressure line, whereby extreme shift of the blades will be effected upon upsetting of the said check valve.

5. In a controllable pitch aircraft propeller having shiftable blades and hydraulically actuated means for altering the pitch angle of the propeller blades, the combination comprising, a fluid pressure regulator rotatable with the propeller and having a distributor valve adapted to control the application of fluid under pressure to the pitch angle altering means, a source of fluid pressure, an accumulator rotatable with the propeller, conduit means connecting the accumulator with the fluid pressure source in advance of the distributor valve, and a control valve in the conduit means normally effecting charge of the accumulator with fluid under pressure from the source, and for selectively exposing the charge of the accumulator to the distributor valve and thence to the hydraulically actuated means, said control valve including a high pressure flow valve, a check valve carried by the flow valve, a piston and spring normally urging the flow valve to a closed position but adapted to back off on exertion of fluid pressure from the accumulator above a predetermined maximum pressure, means for interrupting the control by the distributor valve and for coincidentally unseating the check valve for exposing the piston to the fluid pressure of the accumulator for selectively opening the flow valve, and valve means actuated by the retraction of the piston for applying the full force of the fluid pressure of the accumulator through the distributor valve and to the hydraulically actuated means for shifting the pitch angle of the blades.

6. In a controllable pitch propeller for aircraft, having pitch shiftable blades and fluid pressure actuated means for altering the pitch angle of the blades, and a hollow shaft for mounting the propeller, the combination comprising, an annular regulator mechanism surrounding the shaft and rotatable with the propeller, a pump driven by the regulator to develop a source of liquid pressure and apply the fluid pressure developed to the fluid pressure actuated means, an accumulator also rotatable with the propeller, conduit means including a control valve unit connecting the accumulator with the source of fluid pressure, said accumulator comprising a pair of rigid telescoping shells of annular form entirely clear and unobstructed at their centers to preserve clearance for cannon fire through said hollow shaft, a rigid piston movable between the telescoping shells for dividing the enclosure into a fluid pressure chamber and a preloading chamber, said piston having a skirt defining the minimum volumetric content of the preloading chamber, and means for mounting the accumulator on the propeller concentric with the axis of the propeller shaft.

7. A controllable pitch propeller having blades adjustable about their axes, reversible fluid motive means for actuating the blades through two adjoining ranges of blade inclination, one of which ranges is for normal constant speed operation, and the other of which is for supplemental blade pitch control, a fluid pressure system for the fluid motive means, speed responsive means for controlling the blade angle through the working range, an accumulator in communication with the fluid pressure system, a flow sensitive valve exposed to the pressure in the system for charging

the accumulator, trip means operable upon the flow sensitive valve for exposing the fluid motive means to the pressure of the accumulator, means operable upon the flow sensitive valve when the fluid pressure upon the fluid motive means equals the pressure in the accumulator for closing the accumulator to retain fluid pressure therein against leakage and for a subsequent and reverse application to said fluid motive means, and means operable upon the speed responsive means and upon the trip means for selecting the exposure of the fluid motive means to the accumulator, whereby the blade pitch may be shifted at will into either range from the other range.

8. In a controllable pitch propeller having pitch shiftable blades and a fluid operated system of control with blade motors for altering the blade angle, the combination of means for feathering the blades comprising, a pressure source developed by rotation of the propeller, a cylinder mounted on the hub in front of the blades, a rigid piston traversing the length of the cylinder and dividing it into a preloading chamber and a pressure chamber, passage means connecting the pressure chamber with the fluid operated system, a valve unit inserted into the passage means and operable to admit fluid to the pressure chamber upon rotation of the propeller, and means including a flow valve selectively operable for opening the full charge of the pressure chamber to the fluid operated system whether or not the propeller is rotating.

9. In a constant speed controllable pitch propeller having fluid pressure operated mechanism for adjusting the blade pitch within a working range and a regulator for supplying fluid under controlled pressure to the fluid pressure operated mechanism, the combination of a reservoir in the regulator providing a supply of fluid, pump means for applying the fluid under pressure to the pres-

sure operated mechanism, manually controlled means for selecting the speed level for which the constant speed control will be effected and for shifting the blade pitch to an extreme position outside of the working range, an accumulator having a pressure chamber preloaded against self-expansion, means connecting the pressure chamber with the reservoir and the pressure operated mechanism and under control of said manually controlled means, said connecting means including a valve unit removably mounted on the regulator, and including a spring pressed piston normally stopping return flow from the pressure chamber, a check valve carried by the piston, and a trip rod selectively operable by the manually controlled means for upsetting the check valve, whereby the force of the pressure chamber is then operable upon the piston to compress the spring and allow return flow of pressure fluid from the pressure chamber to the fluid pressure operated mechanism coincident with shifting of the manually controlled means to an extreme position.
